(57) **CLAIM**

The ornamental design for a handle for a sample collector, as shown and described.

DESCRIPTION

FIG. 1 is a perspective view of a handle for a sample collector showing our new design;

FIG. 2 is a right side elevation view thereof, the left side elevational view being a mirror image thereof;

FIG. 3 is a top plan view thereof, the bottom plan view being a mirror image thereof;

FIG. 4 is a front elevational view thereof;

FIG. 5 is a rear elevational view thereof; and,

FIG. 6 is a perspective view of a second embodiment of a handle for a sample collector showing our new design, with the top, bottom, left, right and rear elevational views being the same as the first embodiment.

The broken line showing in FIGS. 1, 4 and 6 are for illustrative purposes only and forms no part of the claimed design.
